UNITED STATES PATENT OFFICE.

RICHARD MILLER, OF NEW BERLIN, OHIO, ASSIGNOR TO WILLIAM H. HOOVER, OF NEW BERLIN, OHIO.

HARNESS-TREE SEAT.

SPECIFICATION forming part of Letters Patent No. 763,994, dated July 5, 1904.

Application filed May 23, 1902. Serial No. 108,665. (No model.)

To all whom it may concern:

Be it known that I, RICHARD MILLER, a citizen of the United States, residing at New Berlin, in the county of Stark and State of Ohio, have invented certain new and useful Improvements in Harness-Tree Seats; and I do hereby declare that the following is a full, clear, and exact description of the same, reference being had to the annexed drawings, making a part of this specification, and to the figures of reference marked thereon, in which—

Figure 1 is a longitudinal section of the seat, showing a side view of the connecting thimble or head in proper position to be connected or seated. Fig. 2 is a longitudinal section of the seat, also a longitudinal section of the thimble or connecting-head, showing the same properly connected to the seat. Fig. 3 is a longitudinal section of the head, a cross-section of the tree showing the parts properly connected together.

The present invention has relation to improvements in the means for connecting the seat and harness-tree together when said parts are formed of sheet metal; and it consists in the novel construction and arrangement hereinafter described.

It will be understood that by forming the seat and tree of stamped metal the parts must necessarily be thin, and hence little metal surrounds the apertures through which it is desired to place screws, and hence there is not a sufficient amount of metal to provide any great number of screw-threaded convolutions.

My improvement consists in providing a connecting thimble or head of the proper length and forming a screw-threaded aperture in the head to receive a corresponding screw-threaded connecting-screw; and it further consists in providing an annular groove upon the periphery of the thimble or connecting-head and in bending the metal of the part or parts to which the thimble or connecting-head is to be attached at an angle, said angle portion being located around and adjacent to the aperture through which the thimble or head is to be passed.

In use when the aperture is formed in the part to which the thimble or coupling-head

is to be attached the metal supporting the aperture is bent at an angle in either direction, the coupling-head brought into position so that the annular groove will receive the periphery of the angle portion surrounding the aperture, after which the thimble or coupling-head is moved endwise, carrying with it the bent or angled portions until it is brought into the position illustrated in Figs. 2 and 3.

In the accompanying drawings, 1 represents a seat which may be of any desired style and is formed of sheet metal by means of a die or dies and is provided with an aperture 2, around which aperture is located or formed the angled flange 3. The thimble or coupling-head 4 is provided with the annular groove 5, which annular groove is formed of such a depth that room is provided to allow the angled flange 3 to be brought into the position illustrated in Fig. 2 and seated in the annular groove 5. The annular groove 5 should be so located with reference to the end of the thimble or coupling-head 4 that when said thimble or coupling-head is brought into its normal position the end of the head will be flush with the surface of the seat or harness-tree, as the case may be. It will be further understood that by my peculiar arrangement I am enabled to provide means for a sufficient amount of metal to provide the desired number of screw-threaded convolutions to properly hold a screw, and thereby securely connect the stamped sheet-metal tree 6 and the stamped sheet-metal seat 1 together and hold said parts in fixed relative position without danger of accidental displacement.

The thimble or coupling-head 4 should be formed of such a length that proper space will be provided between the tree 6 and the seat 1 that the various parts usually placed between said tree and seat can be placed in proper position and held without movement independent of said tree and seat, or, in other words, to properly clamp all the parts together.

I have illustrated my improvement as applied more particularly to the seat 1; but I do not desire to be confined to the attachment

of the thimble or coupling-head to the seat, as it will be understood that it is immaterial so far as the invention is concerned whether the thimble or coupling-head is connected to 5 the seat or to the tree, as it is only a transposition.

It will be understood that by using metal that can be bent the metal adjacent to the groove formed in the thimble of coupling-head 4 can be seated into the groove equal to the depth of the groove, and thereby securely connect the thimble or coupling-head to the seat.

Having fully described my invention, what 15 I claim as new, and desire to secure by Letters Patent, is—

The combination of a stamped seat provided with an aperture, the metal surrounding said

aperture formed bendable, a thimble or coupling-head provided with an annular groove, 20 and the metal surrounding the coupling-head seated into the annular groove equal to the depth of said groove, said coupling-head provided with a screw-threaded aperture, a screw located in the screw-threaded aperture and a harness-tree located beneath the seat, all arranged, substantially as described and for the purpose specified.

In testimony that I claim the above I have hereunto subscribed my name in the presence 30 of two witnesses.

RICHARD MILLER.
